UNITED STATES PATENT OFFICE.

CARL FARKAS AND HERMAN J. JAEGER, OF NEW YORK, N. Y.

INCANDESCENT ELECTRIC LAMP.

933,539.

Specification of Letters Patent. Patented Sept. 7, 1909.

Application filed August 24, 1908. Serial No. 449,870.

To all whom it may concern:

Be it known that we, CARL FARKAS, a citizen of the Kingdom of Hungary, and HERMAN J. JAEGER, a citizen of the United States of America, both residents of New York, in the county and State of New York, have invented certain new and useful Improvements in Incandescent Electric Lamps, of which the following is a specification.

19 This invention has reference to improvements in incandescent lamps.

It pertains particularly to that type of incandescent lamps containing a so called metallic filament of relatively great length embodied in a glass globe of usual size and having a number of loops all in series with each other. Thus the single loops of the filament form one continuous single conductor requiring but two leading-in wires 29 as in any ordinary multiple arc lamp. These long metallic filaments, as is well known, consume but very little current and present a relatively large light emitting surface. Such long metallic filaments made, for instance, of chromium expand by the heat of the electric current when the lamp is lighted. Each loop of the filament accordingly gets longer and, at the same time, slightly softens. Therefore lamps containing metallic filaments cannot be safely burned except when hanging vertically downward with the base at the top and then there is danger of 39 two neighboring loops coming in contact with each other whereby the filament burns 35 out, or one loop may touch the glass wall of the globe, breaking same and destroying the vacuum. When such lamps are mounted with the base at the bottom the danger of 45 losing the lamp is so much greater. For 40 certain purposes it is desirable or necessary to mount the lamps so that the filament is in a horizontal position. The above described lamps cannot be burned horizontally.

The present invention has for its object 45 to produce incandescent lamps with such long, economical, metallic filaments which may be burned horizontally or vertically with the base at the bottom. For this purpose flat, elastic and conductive supports, 50 and flat elastic anchors are provided within the novel lamp. These supports are arranged in such manner that the free ends of the single loops of the filament may be cemented thereto so that all the loops are 55 in series and form one continuous conductor while the elastic anchors support each a loop

proper. The flat metallic conductors and the flat elastic anchors are of novel construction. By virtue of the elasticity of these devices the single loops of the filament are 60 protected against injury and breakage when linear expansion of the loops takes place when the lamp is lighted. Likewise the single loops are protected against tearing when contraction takes place after the current has 65 been turned off.

The invention is illustrated in the accompanying drawing in which:

Figure 1 represents in perspective view an incandescent lamp with metallic filament 70 which embodies in desirable form the present improvements. Fig. 2 illustrates in top plan view the top support for the filament loops, and Fig. 3 is a cross section on line 3, 3 of Fig. 1.

Similar letters of reference denote like parts in all the figures.

The protecting and supporting devices are made of very thin, flat strips of metal which may be secured to a glass rod by fusion in 80 the same manner in which the leading-in wires are sealed into the stem. Accordingly these devices are preferably made of platinum or platinum nickel alloy or other suitable conductive metal which is ductile 85 enough to be formed into very thin sheets and strips and possesses the required elasticity.

In Fig. 1 of the drawing *a* represents the globe or vacuum chamber which usually 90 is of elongated or pear shape, *b* is the stem sealed into the globe in the usual manner and carrying the leading-in wires *c*, *d*. To the solid top portion of the stem is fused a thin standard or post of glass, preferably 95 a thin glass rod *e*. A small rim *f* is formed in the lower portion of the standard. To this rim are secured by fusion three flat metallic conductors at a distance of 90° from 100 each other while the wires *c*, *d* are bent horizontally over in the free space of the circle and in a horizontal plane with the three conductors. Close to the top of the glass rod *e* there is formed a rim *g* to which are secured or fused four flat elastic anchors, 105 which however need not be made of metal or conductive material.

The elastic supports *h*, *i*, *j*, fused to the rim *f* of the glass rod *e* consist each of a flat thin strip of platinum having a long horizontal portion *k* which is bent downward and formed into a short horizontal strip *l*

at a right angle to the portion *h*, as is shown in Figs. 1 and 3. Thus these supports are practically T shaped.

Four flat elastic anchors are secured to the rim *g* at the top of the glass rod *e*. These anchors *m*, *n*, *o*, *p* are arranged in a horizontal plane at 90° apart. The anchors are not arranged in the same vertical plane with the supports below, but in vertical planes between them for the reason which will be stated below. Each elastic anchor consists of a flat horizontal strip formed into a hook *q* as shown in Fig. 1. The anchors are made of flat elastic metal strips preferably of platinum, platinum alloys, nickel, aluminum, or bronze, the strips from which they are made must be very thin, so as to be elastic.

Four filament loops are shown in Fig. 1 of the drawing in connection with the three elastic conductive supports and the four elastic anchors. The loops have the shape of a hair pin. They are narrow at the top and the free ends are relatively far apart. The free ends are cemented to the metallic supports and the loops hang in the hooks of the anchors. For this reason the anchors are not in the same vertical planes with the supports. The loops are arranged as follows: The loop *r* is cemented with one free end to the leading-in wire *d*, it passes over the hook of the anchor *m* and its second free end is cemented to the neighboring side end of the support *h*. The loop *s* is cemented with one free end to the second side end of the support *h*, it passes over the hook of the anchor *n* and its second free end is cemented to one side end of the support *i*. The loop *t* is cemented with one free end to the second side end of the support *i*, it passes over the hook of the anchor *o*, and its second end is cemented to the neighboring side end of the support *j*. The loop *u* is cemented with one

free end to the second side end of the support *j*, passing over the hook of the anchor *p*, it runs down to the leading-in wire *c* to 45 which its second free end is cemented.

The filament loops cemented to the flat elastic supports and hanging in the hooks of the flat elastic anchors do not sag when linear expansion takes place during the 50 burning of the lamp. The hooks of the elastic anchors leave some room for expansion. When the current is turned off the loops become cold and contraction sets in but the danger of breaking is avoided because the cold, stiff loops are protected by the elastic supports which then slightly give way.

We claim as our invention:

An incandescent electric lamp with metallic filament, comprising a vacuum chamber with stem and leading-in wires, a standard or post of non-conductive material secured to the top portion of the stem, a set of flat, T shaped, elastic, conductive supports for the filament loops secured to the bottom portion of the standard, a set of flat elastic anchors with hooks at the ends secured near the top end of the standard, and a metallic filament consisting of four loops 70 hanging in the hooks of the elastic anchors and cemented alternately with their free ends to the leading-in wires and the free side ends of the T shaped supports so that the loops are connected in series. 75

In testimony whereof we have hereunto set our hands in the presence of two subscribing witnesses.

CARL FARKAS.
HERMAN J. JAEGER.
